The ornamental design for a cap of a toy dart, as shown and described.

DESCRIPTION

FIG. 1 is a first perspective view of a new design for a cap of a toy dart.

FIG. 2 is a second perspective view thereof;

FIG. 3 is a left side view thereof;

FIG. 4 is a right side view thereof;

FIG. 5 is a front view thereof;

FIG. 6 is a back view thereof;

FIG. 7 is a top view thereof; and,

FIG. 8 is a bottom view thereof.

The dart body is shown in broken lines for illustrative purposes only and forms no part of the claimed design.
